UNITED STATES PATENT OFFICE.

JOHN H. PACKER, OF NEWPORT, KENTUCKY, ASSIGNOR OF ONE-HALF TO
CHARLES N. AVERY, OF CINCINNATI, OHIO.

METALLIC ROOFING.

SPECIFICATION forming part of Letters Patent No. 393,516, dated November 27, 1888.

Application filed August 17, 1888. Serial No. 223,037. (No model.)

To all whom it may concern:

Be it known that I, JOHN H. PACKER, a citizen of the United States, and a resident of the city of Newport, in the county of Campbell and State of Kentucky, have invented certain new and useful Improvements in Methods of Manufacturing and Applying Metallic Roofing, of which the following is a specification.

In the accompanying drawings, forming part of this specification, Figure 1 is a perspective view of a sheet of metal with the edge turned over, grasping the cleat or fastening, illustrating the first step of the operation of forming the complete sheet for roofing. Fig. 2 is a perspective view of the completed sheet ready for packing and shipping. Fig. 3 is a section taken at the line *x x*, Fig. 2. Fig. 4 is a perspective view of the completed sheet, with the cleat bent back in a reversed position from that shown in Fig. 2, and ready for attaching to the roof. Fig. 5 is a section taken at the line *y y*, Fig. 4. Fig. 6 is a perspective view illustrating several sheets joined before closing the standing seam. Fig. 7 is a cross-section of a completed joint or standing seam closed, and the sheet-metal roofing attached to the roof.

The cleats A, previous to being attached to the roofing sheet, are plain strips. These strips are laid upon each sheet S, at suitable distances apart, with their ends nearly to the edge of the sheet. The flange B on the edge of the sheet is now turned over, grasping the cleats and holding them in place, as shown in Fig. 1. The V-shaped fold C is now formed in the edge of the sheet, as shown in Figs. 2 and 3, by any of the means ordinarily employed for that purpose. The cleats are bent into the V with the sheet, as shown; but the tail *a* of each cleat still lies flat against the under side of the sheet. In the other edge of the sheet a simple flange or V-fold, D, is formed. In this condition, as shown in Figs. 2 and 3, the sheets may be closely nested for packing.

In applying the sheets to the roof the tail *a* of each cleat is bent forward, as shown in Figs. 4 and 5, projecting beyond the edge of the sheet. These tails *a* are next attached to the roof by nails or other suitable means. The next sheet is attached to the sheet already laid by slipping its flange D under the fold C of

the first sheet, as shown in Fig. 6, and then bringing the second sheet down flat onto the roof. The fold C is next tightly crimped together with suitable crimping-irons, forming 55 a tight standing seam, as shown in Fig. 7.

Among the various advantages arising from the use of my invention are the following, viz:

First. The cleats can be moved by sliding them along the sheet while in the condition 60 shown in Figs. 4 and 5, the cleats remaining all the time connected to the sheet, as shown in said last-named figures. By this adjustability the cleats can be placed at any distance apart to be properly applied to the board sheeting 65 or rafters, located at varying distances apart.

Second. Another advantage is, that the cleat is attached to the sheet when shipped, the V-groove having been already formed in it as well as in the sheet, and is in convenient 70 position for ready and immediate application to the roof, thereby effecting a great saving of labor and of time when laying the metal roof.

Third. The combination of the metal sheet 75 and cleat, as formed and combined when shipped, (see Figs. 3 and 4,) is of a simple construction, and such as can be applied by any person of ordinary intelligence.

Fourth. The cleat may be termed a "secret" 80 one, as when the metal roofing is laid the cleat is completely hidden from view, and no portion of it is exposed to the action of the weather, and both it and the heads of the nails or bolts connecting it to the roof are entirely covered.

Fifth. Complete provision is made by my invention for the expansion and contraction of the metallic roofing.

What I claim as new, and desire to secure by 90 Letters Patent, is—

The process of forming roofing-plates, consisting of attaching underlying straight cleats, then folding over the edge of the sheet, and subsequently making a V-fold in sheet and 95 cleats, substantially as and for the purposes specified.

JOHN H. PACKER.
